MINE SKIP

Guy Lefanu Saunders, Toronto, Ontario, Canada

Application September 11, 1948, Serial No. 48,843

7 Claims. (Cl. 214—120)

1

This invention relates to a mine skip for use particularly in raising ore from a mine to the ground surface.

Mine skips or buckets are used in raising ore from the various levels of a mine to the surface. The skips ordinarily are in the form of elongated buckets adapted to be carried on bails which form a frame within which the bucket is carried and which slide on guides or on relatively heavy timbers provided for this purpose in the mine shaft. The skips are raised from and lowered into the mine shaft by a cable.

The conventional skips have several important disadvantages. The skips are as large as possible in order to raise maximum loads, within the limits of the mine shaft and the cable hoist apparatus of course, and they must be strongly reinforced to withstand the shocks and stresses to which they are subjected in loading and raising.

In the use of conventional skips, the mine head frame must be higher than the dumping chute by at least twice the length of the bucket, plus the overwind allowance, and an arrangement of guides and tracks are provided to turn the bucket upside down to dump the load into a chute which usually leads to a storage bin. The conventional skips thus involve costly head frame structures and dumping equipment.

Buckets which empty through the bottom have been proposed but difficulties are found in their use. For example, the bottom of the bucket must be capable of withstanding the shock of the bulk load of heavy ore dropped into it, and it must carry the load safely without danger of leakage of ore or of the bottom swinging open as the skip is raised to the surface. Also, at the dumping position, the skip must be swung clear of the mine shaft before any of the load is discharged.

One of the important objects of the present invention is to provide a mine skip which empties through the bottom and which is devised with shock absorbers which absorb the shock of the bulk load as it is dumped into the skip at the loading point.

A further important object of the invention is to provide a bottom dump mine bucket in which the bottom is supported firmly in its closed position against shock during loading and raising, and which opens freely when the bottom of the bucket is swung outwardly of the skip frame when it has reached its dumping position.

A still further object of the invention is to provide a simple arrangement of sealing the joint between the walls and the bottom of the bucket

2

to prevent leakage of material during loading and raising.

A still further object of the invention is to provide a relatively simple arrangement of guides for swinging the lower end of the bucket away from the mine shaft and clear of the bottom supporting member as the skip reaches its dumping position.

The skip of the present invention comprises, in general, a frame adapted to fit and move within guides, an elongated bucket resiliently suspended from the top of said frame, a bottom hingedly attached to said bucket, resiliently mounted means carried by said frame adapted to support said bottom in the loading and raising of said bucket, means carried by said bucket adapted to engage tracks spaced from said guides for swinging the lower end of said bucket out of the frame and away from the bottom supporting member, and means for closing the joint between the lower end of the bucket walls and the hinged bottom member.

An understanding of the manner in which the above and other objects of the invention are attained may be had from the following description, reference being made to the accompanying drawings in which:

Figure 1 is a perspective view of a mine skip embodying the features of the present invention in a raising or lowering position;

Figure 2 is a perspective view of the skip in a dumping position;

Figure 3 is a detail view in section taken along the line 3—3, Figure 1;

Figure 4 is a detail view in section taken along the line 4—4, Figure 1;

Figure 5 is a detail view partly in section taken along the line 5—5, Figure 1; and

Figure 6 is an enlarged detailed view in section of the lower end of the skip.

Referring to the drawings, the mine skip of the present invention includes, in general, a frame comprised of bails 10 having a transverse draw bar 11, an elongated bucket 12 and associated parts, and a door supporting apparatus, all of which are described in detail hereinafter.

The bails 10 are in the form of relatively heavy channel beams or other structural shapes adapted to fit around three sides of the mine timbers 13 on which they slide. Usually a wearing shoe is interposed between the opposing faces of the timbers and the bails. The bails 10 and the draw bar 11 form a frame within which the bucket 12 is suspended.

The draw bar 11 extends transversely of the

upper end of the bails 10 and is provided with centrally disposed hanging bars 15 to which the mine cable 16 may be firmly secured, such as by bolts 17. The ends of the draw bar are secured in the enlarged upper ends 18 of the bails 10, described hereinafter.

The manner in which the bucket is resiliently suspended from the draw head is illustrated in detail in Figure 3. Hangers 20 in the form of relatively heavy members are formed by upward extensions of two opposing sides of the upper end of the bucket. These hangers 20 are designed to withstand the loads to which they are exposed. A shaft 21 is extended through housings 23 provided in hangers 20 secured to opposing sides of the bucket. Rubber shock absorbers 22 are inserted between the housing 23 and the hanger 20. The shaft is journalled in resiliently mounted bearings 24 provided in the draw head 18. The bearings 24 are mounted in bearing housings 25 provided in each side of the draw head. Each bearing housing is spaced from the draw head by rubber blocks 26 or other suitable form of shock absorber. The arrangement of the shaft 21 provides in effect a resiliently mounted pivotal connection between the draw head and the upper end of the bucket.

The bucket 12 ordinarily is of rectangular shape and is formed of relatively heavy side plates capable of withstanding the loads to which it is subjected. A pair of rollers or wheels 30 are rotatably mounted adjacent the edges of the lower ends of the sides of the bucket. These rollers or wheels are adapted to engage tracks 39 provided at the dumping position of the shaft to swing the lower end of the bucket out of the frame. The wheels 30 are rotatably mounted on short shafts journalled in housings 41 secured to the sides of the bucket, as illustrated in Figure 5.

The bucket is provided with a safety latch to hold it firmly within the bails 10 during raising and lowering.

A preferred form of safety latch comprises a latch catch 31 in the form of a stud extending from each side of the bucket about midway of its length and positioned adjacent to a bail. This latch catch is normally engaged by the hooked end 32 of an L-shaped latch 33 which is pivotally secured to the bracket 35 on the side of each bail remote from the mating stud 31.

The latch is provided with an arm 36 which carries an outwardly extending roller 37. This roller 37 is adapted to engage a track 38 positioned near the dumping position of the shaft which, as the bucket moves upwardly, raises the latch from the stud 31 immediately prior to the engagement of the wheels 30 with the dump track 39.

Stone blocks 40 are provided on the sides of the skip normally to aid in holding the skip in alignment with the bails.

The base or bottom 50 of the bucket is hingedly secured to the lower rearward edge of the bucket. Preferably, as illustrated in detail in Figures 1, 2 and 4, the hinges are in the form of heavy straps which are pivotally secured to the bucket adjacent to but slightly above the lower end and are firmly secured thereto. This arrangement of hingedly securing the bottom to the bucket permits the bottom to open the full area of the lower end of the bucket without any restriction which would interfere with the discharge of the load when the bucket is in its dumping position, as illustrated by Figure 2.

The bottom of the bucket is in the form of a heavy casting of a type suitable to carry safely the loads to which it is subjected. The bottom is resiliently and pivotally secured to the rearward face of the bucket adjacent to but spaced apart from the lower edge thereof by a shaft 60 which is journalled in roller bearings 61 mounted in bearing housings 62 which are carried by castings 65 secured to each side of the skip bucket. The housings 62 are spaced from the hinges 63 by rubber or other suitable shock absorbing blocks 64, as illustrated by Figure 4.

The bottom is supported resiliently and firmly during loading, raising and lowering by a cam track and roller arrangement illustrated by Figure 6. In this arrangement, a shaft 70 is journalled in an outwardly extending housing 71 secured to or otherwise carried by each bail 10 below the bucket. A rubber or other suitable shock absorbing block 75 is interposed between the ends of the shaft and the housing 71. A wheel or roller 72 is mounted at each end of the shaft 70 between the housings 71. Preferably, roller bearings 73 are interposed between the rollers and the shaft and rubber or other suitable shock absorber blocks 74 are interposed between the bearing housing 71 and the rollers.

The rollers 72 move on cam tracks 76 which are secured to the underside of the bottom 50, the tracks being designed so that when the bucket is in alignment with the bails the bottom is held firmly in a closed position, as illustrated by Figure 1, and as the lower end of the bucket is swung out of the bails, the curvature of the cam tracks permits the bottom to open to its fullest extent, as illustrated by Figure 2.

The joint between the bottom 50 and the lower edges of the bucket are sealed by relatively heavy rubber strips 80 which are secured to the lower edges of the bucket by bolts 81. Preferably parallel strips are employed which extend downwardly to contact the upper surface of the bottom 50 and are of sufficient length to provide a seal between the edges of the bucket and the bottom.

The bottom 50 of the bucket is provided with a wearing plate 85 and also is preferably provided with a shock absorber 86, such as a thick block of wood, between the wearing plate 85 and the bottom, the assembly being detachably secured together by bolts 87.

In the use of the skip, the bucket is locked in alignment with the bails during loading, raising to its dumping position and lowering from its dumping position. As the skip is raised to the dumping position, the end of the safety latch engages the track 38 and is released, following which the roller 37 engages the dump track 39 and the lower end of the bucket is swung outwardly from the bails and the bottom is permitted to open. Preferably, the cam track 76 is designed so that the bottom is held firmly in its closed position until it is over the unloading chute, clear of the shaft. After dumping its load, the skip is lowered, into the mine shaft and as it is lowered the bucket is returned to its position in alignment with the bails and locked in position by the safety latch.

The skip of the present invention possesses a number of important advantages. The mine shaft head frame may be built substantially lower than with conventional skips and the relatively costly dumping arrangements are eliminated with attendant important savings in construction costs. The bucket empties instantaneously as

soon as it is clear of the mine shaft which increases the amount of ore which can be raised in a specified time. The arrangement of the shock absorbers for the parts subjected to the shock of the bulk load dumped into the bucket at the loading levels minimizes the wearing effect of the load and eliminates the difficulties which heretofore have offset the advantages of bottom dump buckets.

It will be understood, of course, that modifications may be made in the preferred embodiment of the invention described and illustrated herein without departing from the scope of the invention defined by the appended claims.

What I claim as new and desire to protect by Letters Patent of the United States is:

1. A mine skip comprising a frame adapted to fit and slide within guides, an elongated bucket resiliently suspended from the top of said frame, a bottom for said bucket, means for hingedly attaching said bottom to said bucket comprising a shaft journalled in spaced bearings mounted in housings carried by said bucket adjacent to but spaced from the lower edge of the rearward face of said bucket, a hinge strap carried by said shaft and secured to the undersurface of said bottom, a shock absorber between each bearing housing and the adjacent hinge strap, means adapted to support said bottom in the loading and load carrying positions of the bucket, means carried by said bucket adapted to engage tracks spaced from said guides for swinging the lower end of said bucket out of the frame away from the bottom supporting means and means for closing the joint between the bucket walls and the hinged bottom member.

2. A mine skip comprising a frame adapted to fit and slide within guides, means for suspending a bucket in said frame which comprises a transverse member extending between opposing sides of said frame and firmly secured thereto, a transverse shaft journalled in spaced bearings mounted in housings carried by said frame below said transverse member, shock absorbers between said bearing housings and said transverse member, a hanger mounted at each end of said shaft between said bearings and secured to the upper end of the bucket, a shock absorber between the shaft and each hanger, a bottom hingedly attached to said bucket, resiliently mounted means adapted to support said bottom in the loading and load carrying positions of the bucket, means carried by said bucket adapted to engage tracks spaced from said guides for swinging the lower end of said bucket out of the frame away from the bottom supporting means, and means for closing the joint between the bucket walls and the hinged bottom member.

3. A mine skip adapted to fit and slide within guides, an elongated bucket resiliently suspended from the top of said frame, a bottom hingedly attached to said bucket, resiliently mounted means adapted to support said bottom in the loading, raising and lowering positions of the bucket which comprises a shaft journalled in spaced housings carried by said frame below said bucket, shock absorbers between said housing and said frame, at least one cam track carried by the undersurface of said bottom, and a resiliently mounted roller mounted on said shaft adapted to engage each cam track, means carried by said bucket adapted to engage tracks spaced from said guides for swinging the lower end of said bucket out of the frame away from the bottom supporting member, and means for closing the joint be-

tween the bucket walls and the hinged bottom member.

4. A mine skip comprising a frame adapted to fit and slide within guides, an elongated bucket pivotally suspended from the top of said frame, a bottom for said bucket, means for hingedly attaching said bottom to said bucket comprising a shaft journalled in spaced bearings mounted in housings carried by said bucket adjacent to but spaced from the lower edge of the rearward wall of the bucket, a hinge strap carried by said shaft and secured to the under-surface of said bottom, means adapted to support said bottom in the loading and load carrying positions of the bucket, means carried by said bucket adapted to engage tracks spaced from said guides for swinging the lower end of said bucket out of the frame away from the bottom supporting means, and means for closing the joint between the bucket walls and the bottom member.

5. A mine skip comprising a frame adapted to fit and slide within guides, an elongated bucket pivotally suspended from the top of the frame, a bottom for said bucket, means for hingedly attaching said bottom to said bucket comprising a shaft journalled in spaced bearings mounted in housings adjacent to but spaced from the lower edge of the rearward wall of said bucket, means adapted to support said bottom in the loading and load carrying positions of the bucket, compressible means adapted to close the joint between the lower edges of the bucket walls and the bottom member, and means carried by said bucket adapted to engage tracks spaced from said guides for swinging the lower end of the bucket out of the frame and away from the bottom supporting means.

6. A mine skip comprising a frame adapted to fit and slide within guides, an elongated bucket pivotally suspended from the top of said frame, a bottom for said bucket, means for hingedly attaching said bottom to said bucket comprising a shaft journalled in spaced bearings mounted in housings adjacent to but spaced from the lower edge of the rearward face of said bucket, compressible means secured to the lower edges of said bucket and adapted to close the joint between the lower edges of the bucket walls and the bottom member, means for supporting said bottom member in a closed position in the loading and load carrying positions of the bucket, means for latching said bucket in alignment with said frame, means carried by said bucket adapted to engage tracks spaced from said guides for swinging the lower end of the bucket out of the frame away from the bottom supporting means and means for releasing said latch to permit the lower end of the bucket to swing out of its alignment with said frame.

7. A mine skip comprising a frame adapted to fit and slide within guides, an elongated bucket pivotally suspended from the top of said frame, a bottom for said bucket comprising a relatively heavy casting having a wearing plate secured to the load carrying surface thereof and shock absorbing means between said wearing plate and said casting, means for hingedly attaching said bottom to said bucket comprising a shaft journalled in spaced bearings mounted in housings adjacent to but spaced from the lower edge of the rearward face of said bucket, means adapted to support said bottom in the loading and load carrying positions of the bucket, compressible means adapted to close the joint between the lower edges of the bucket walls and the bot-

tom member, and means carried by said bucket adapted to engage tracks spaced from said guides for swinging the lower end of the bucket out of the frame and away from the bottom supporting means.
